(57) **CLAIM**

We claim the ornamental design for a LED lamp, as shown and described.

DESCRIPTION

FIG. 1 is a front perspective view of a LED lamp showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures show portions of the LED lamp which form no part of the claimed design.

The diagonal lines in the figures represent a reflective surface.
